IMPULSE RECEPTION

Paul Kotowski, Sigmund Hugo Sonnenfeld, and Gottfried Vogt, Berlin, Germany, assignors to Telefunken Gesellschaft für Drahtlose Telegraphie m. b. H., Berlin, Germany, a corporation of Germany

Application April 20, 1938, Serial No. 203,104
In Germany April 22, 1937

1 Claim. (Cl. 250—20)

In the reception of impulses it often happens that in addition to feeble ground wave impulses, one or more powerful ionosphere impulses are impressed on the receiver. The receiver apparatus which is very responsive and sensitive to ground-wave impulses is overloaded because of the fact that the sky-wave impulses or echoes are occasionally as much as 100 times stronger.

Such overloading causes in the last high-frequency stages and also in the audio frequency stages the production of grid currents, and these cause the coupling condensers, especially those in the audio frequency stages, to become charged. The apparatus will be blocked for a time and will become ready for operation only after an interval of time governed by the charging and discharging time constants of the R—C elements.

Where automatic volume controlled receiver apparatus is concerned, there occurs in addition an overall retrogressive regulation of the responsiveness. Identical disturbing actions arise upon the production of strong atmospheric. Now, the method here disclosed according to the invention is designed to suppress both the said atmospheric disturbances as well as powerful ionosphere echoes. In order to rapidly reduce the receiver sensitivity upon the reception of overloads, the blocking time constants of the capacitors and resistors in the grid circuits of the radio frequency, intermediate frequency and audio frequency stages according to this invention are to be made roughly equal to the impulse length.

In order that undue voltage peaks may be entirely prevented from reaching the audio frequency part, a resistance of the approximate size of the alternating current resistance of the grid-filament path is included in the grid lead of the last radio, intermediate and audio frequency tubes of each stage, according to a further object of this invention. The said resistance is intended to prevent a further growth of the grid alternating potentials upon incipient flow of grid current (see Fig. 1, resistances R_v).

A further method of eliminating atmospheric and of rendering the effects of marked ionospheric echoes harmless, according to another object of the invention, consists in the provision of amplitude limiting means or output limiters. The arrangement is so that the receiver apparatus has its maximum or optimum responsiveness or sensitivity in the presence of field strengths of the ground-wave impulse of, say, up to 50 microvolts per meter. After this point has been reached, a regulator action starts which may even have a drooping characteristic. The receiv-

er then has its maximum sensitivity in the presence of potentials which surpass its own inherent noise by a factor of, say, 1 to 20. This invention will be better understood from the following description when considered in connection with the accompanying drawings, in which Figure 1 is a schematic diagram of an embodiment of this invention, and Figure 2 is a curve illustrating the operation of this invention.

Referring now to Fig. 1, a portion of a radio receiver is illustrated to show the application of an automatic volume control circuit. Reduction of sensitivity is effected in the usual way by means of a diode rectifier coupled to the intermediate frequency amplifier. The rectified voltage is applied to the control grids of the radio frequency pentodes. Unlike the usual control systems, however, the charging time constant of the volume control network is of the same order of magnitude as the impulse, say, 1 microsecond. The discharging time constant for restoring the normal sensitivity is so chosen that the receiver sensitivity is normal upon arrival of the following ground impulse or direct impulse. Reference is made in this connection to Figure 2 where the amplitudes of the incoming ground impulse *a* and consecutive echoes *b₁*, *b₂*, and *b₃* are plotted against time *t*. This time constant is governed by the elements R_v, R', and C, Fig. 1. The dotted line indicates the limiting effect of the volume control system.

Under practical conditions, low time constants are obtained by reducing the resistances and the condensers of the R—C means, though the fluctuation of the internal resistance of the diode must here be duly taken into consideration. Small time constants, moreover, offer the advantage that low-pitched modulation frequencies will not be transmitted because of the smallness of the values of R and C. In fact, they cause downward regulation of the low modulation frequencies. In other words, if an impulse transmitter radiates an appreciable hum this sound will appear only to a very small degree in the incoming signals.

Another chance of using the method here disclosed is that in a heterodyne receiver apparatus either oscillating of the oscillator is prevented for a certain length of time or that the oscillator is detuned by ways and means well known in the art. In either case, the starting point and the time constant must be chosen and fixed in the presence of conditions as hereinbefore indicated.

What is claimed is:
A receiver for the reception of short signal

- pulses separated by discrete intervals, said receiver having means for rectifying said pulses to produce a charging pulse, a capacitor, means for applying said charging pulse to said capacitor to charge said capacitor within a time comparable to the duration of said signal pulse, means for discharging said capacitor within a time com-

parable to one-half the length of said discrete intervals, and means for reducing the sensitivity of said receiver in accordance with the amplitude of the voltage across said capacitor.
